UNITED STATES PATENT OFFICE.

FRANK W. RICHEY, OF CHICAGO, ILLINOIS, ASSIGNOR TO GENERAL ELECTRIC COMPANY, A CORPORATION OF NEW YORK.

RAIL-BOND.

No. 867,415.

Specification of Letters Patent.

Patented Oct. 1, 1907.

Application filed December 5, 1902. Serial No. 133,960.

To all whom it may concern:

Be it known that I, FRANK W. RICHEY, a citizen of the United States, residing in the city of Chicago, county of Cook, State of Illinois, have invented certain new and useful Improvements in Rail-Bonds, of which the following is a specification.

My invention relates to rail bonds, and its object is to provide a bond in which the connection or union between the body portion of the bond and the terminal heads shall be complete and perfect, thus forming a homogeneous structure.

It is only by the formation of a complete and perfect union between the body portions of the bonds and the terminal heads that satisfactory electrical conductivity of the bonds can be obtained, and such complete union also adds to the life of the bond, and thus enhances materially its intrinsic value.

Heretofore, in the construction of bonds, where a welding operation has been employed, the presence of a metallic oxid, for instance, copper oxid, if copper was the metal employed, has prevented that complete and extended union necessary to the formation of a homogeneous structure, which is essential to satisfactory and efficient results.

It has been found that in the operation of welding the parts, as heretofore carried out only the centrally disposed portions of the terminal heads were united to the body portion of the bonds, the outer portions of the contacting area between the said terminals and the body portions of the bonds having been prevented from uniting by the presence of an oxid which formed during the heating of the bond terminals, such formation of oxid being due to the presence of air.

The means employed by me to secure the desired union between the body of a bond and its terminal head, is described hereinbelow and is illustrated in the accompanying drawings forming a part of this specification, and in which,

Figure 1 is a plan view of a rail bond in process of construction with the small cover plate in place at one end only of the bond. Fig. 2 is a section along the line 2-2 of Fig. 1. Fig. 3 is a plan of one of the terminal heads. Fig. 4 is a sectional view along the line 4-4 of Figs. 1 and 2. Fig. 5 is a side elevation of one of the terminal heads. Figs. 6 and 7 are edge and side views, respectively, of one of the cover plates.

In the drawings, the numeral 1 designates the body portion of a rail bond, the said body portion consisting of a series of flat ribbon-like metallic strips arranged side by side or in parallelism, or convolutions of a single, flat, metallic strip, the said body portion of the bond having its opposite ends formed into loops 2, as clearly indicated in Fig. 1 of the drawings. The flat ribbon-like strips are preferably arranged in two

sets, as shown, and each set is provided with a curve 55 or bend 3, as clearly shown in Fig. 1.

4 designates a terminal head or member having a reduced attaching portion 5 and an enlarged flattened out portion 6. The head is provided with a flange 10 somewhat wider than the width of the ribbon like 60 metallic strips constituting the body of the bond. The flange 10 extends upward from the outer periphery of the portion 6. Each of the heads is also provided with a stud or projection 8 which is preferably round, as indicated by dotted lines 1 and 3 of the 65 drawings, and extends upward from the flattened out portion 6 a distance substantially equal to the width of the flange 10.

The space between the stud or projection 8 and the flange 10 forms a channel 7 into which the loop 2 of the 70 body portion of the bond is received, a suitable opening 11 being formed in the flange 10 through which the strips forming the body portion of the bond pass. The height of the stud 8 is sufficiently greater than the width of the strips so that when pressure is applied 75 as hereinafter stated the wedge like portion 9, shown in Figs. 1 and 3, is formed and the bight of the loop thus completely filled. If desired, the wedge-like portion may be formed when the head is forged in which case its height should be equal to the width 80 of the metallic strips constituting the body portion of the bond.

12 designates a plate of circular contour which is adapted to be placed within the space surrounded by the upper portion of the flange 10, as clearly shown at 85 the right hand side of Figs. 1, 2, and 4, of the drawings.

In the construction of my device, the head may be formed in any suitable manner, preferably by forging, the body portion of the head, the projection 8 and the flange 10 being simultaneously formed. After the 90 head has been formed, the loop 2 is placed within the depression or channel 7 after which the plate 12 is placed in position above the said loop, and the projection 8, the terminal heads being then placed within a die and the parts while cold are subjected to a pressure sufficient to turn the upper portion of the flange 10 over upon the greater portion of the peripheral edge of the plate 12, so that the said plate and the body portion of the bond are securely attached to the said head. In the operation of turning the flange 10 over 100 upon the said plate, the air is completely removed from the space formed by the surrounding walls of the plate 12, flattened out portion 6, and the flange 10.

After having been subjected to pressure within a die as above stated, the space aforesaid is completely 105 filled by the stud 8 and the strips forming the loop 2 of the body portion of the bond, the upper portion of the head 4, loop 2 and plate 12 being compacted into

a substantial solid mass from which all air is permanently excluded by the pressure. As a result the formation of an oxid is prevented during the heating which the terminals thereafter undergo preparatory to subjecting the same to pressure for the purpose of securely welding the terminal head 4, plate 12 and loop 2, together to form a homogeneous structure. In welding the said parts together, the head 4 may be placed in a die so that a small portion of its upper 10 enlarged end is allowed to project, after which a hammer of suitable construction is dropped upon the projecting end, to flatten it out, and cause the several parts to unite into a compact, homogeneous structure.

Having thus described my invention, I claim:

- 15 1. A rail bond comprising a body portion and terminal heads, the body portion surrounding a projection upon each of the heads, a plate located over each of said loops and said projections, and each plate being secured in position by an overturned portion of the respective terminal heads compressed upon it.
- 20 2. A rail bond comprising a body portion and terminal heads, the body portion surrounding a projection upon each of the heads, a plate located over each of said loops and said projections, each plate being secured in position by an overturned portion of the respective terminal heads compressed upon it, the said body portion, terminal heads and plates being welded together to form a homogeneous structure.
- 25 3. A rail bond comprising a body portion provided with loops at its opposite ends, terminal heads each provided with a projection upon its upper end, a flange surrounding each of said projections but separated therefrom by a space in which one of said loops is placed, a plate located over each of said loops and the end of the corresponding

projection, said flanges being turned over on the plates, 35 and the terminal heads, loops and plates being welded together.

4. A rail bond comprising a body portion provided with loops at its opposite ends, terminal heads each provided with a projection centrally disposed on its upper end, one 40 of said loops surrounding each of said projections, a plate located over each of said loops and engaging the end of the corresponding projection, a flange surrounding each of said loops and said plates, the edge of said flange being turned over upon the greater portion of the peripheral 45 edges of said plates, the body portion, heads and plates being compacted and welded together into a homogeneous structure.

5. A rail bond comprising a terminal head formed with a projection centrally disposed on one of its ends and a 50 flange surrounding said projection but separated therefrom by a space, a body portion having a portion looped about said projection and located within said flange, and a plate placed over the looped end of the body portion and the end of said projection, said plate being secured to the 55 flange and to the projection.

6. A rail bond comprising a terminal head formed with a projection centrally disposed on one of its ends and a flange surrounding said projection but separated therefrom by a space, a body portion having a portion looped about 60 said projection and located within said flange, and a plate placed over the looped end of the body portion and the end of said projection, said plate being welded to the end of the projection and to the flange.

In testimony that I claim the foregoing as my invention, 65 I have hereunto signed my name this twenty-fourth day of November, A. D. 1902.

FRANK W. RICHEY.

In the presence of—

THOS. K. LANCASTER,
ARTHUR E. PAIGE.
